UNITED STATES PATENT OFFICE.

ETIENNE WITZBERGER, OF CARNEGIE, PENNSYLVANIA, ASSIGNOR TO WITZBERGER HEATING APPLIANCES COMPANY, OF CARNEGIE, PENNSYLVANIA, A CORPORATION OF PENNSYLVANIA.

HEATER.

Application filed May 27, 1921. Serial No. 473,096.

To all whom it may concern:

Be it known that I, ETIENNE WITZBERGER, a citizen of the United States, residing at Carnegie, in the county of Allegheny and 5 State of Pennsylvania, have invented new and useful Improvements in Heaters, of which the following is a specification.

This invention relates to heating devices, and more particularly to a heater adapted 10 to utilize gaseous fuel and employing heating elements of refractory material which are heated to incandescence.

One of the main objects of the invention is to provide a heater of the character 15 stated which may be readily formed from sheet metal so as to be produced at small cost. A further object is to provide a heater in which the walls of the body or casing are prevented from becoming heated, thus permitting the heater to be readily handled 20 and, if desired, to be placed adjacent to the wall of a room without danger of setting fire to the same. A further object is to provide a heater in which the products 25 of combustion may be collected in a suitable hood and permitted to escape through a flue, this hood acting as a supplemental heating device for heating air circulated about the hood. Further objects will appear from the 30 detailed description.

In the drawings:

Figure 1 is a front view of a heater constructed in accordance with my invention;

Figure 2 is a central horizontal sectional 35 view through the heater;

Figure 3 is a central vertical sectional view;

Figure 4 is a section taken substantially on line 4—4 of Figure 3;

Figure 5 is a fragmentary detail of the 40 means for securing the locking plate.

The body of the heater includes a back plate 1 which is secured at its ends by seams 2, or in any other suitable or preferred manner, to the rearward edges of 45 side plates 3. Each of these side plates includes an outwardly and forwardly inclined element 3^a from the forward edge of which extends an element 4^a parallel with the 50 rearward portion of the plate. The forward portion of each element 4^a is formed to provide a cylindrical roll or post 5 which serves to materially reinforce the front of the structure while presenting a 55 neat appearance, each of these rolls has at

its lower end a disc 6 of greater diameter than the roll, these discs acting, with posts 5, to provide foot members for supporting the front of the casing. A disc 7 is secured in the top of each post and is provided with 60 an ornamental knob 8 to give a neat finish to the posts.

A lower front plate 9 is secured between elements 4^a of side plates 3, this plate being inclined upwardly and inwardly of the body 65 or casing 1. An upper front plate 10, which is also inclined upwardly and inwardly of the body is secured at its lower edge to the upper edge of plate 9. The upper edge of plate 10 is secured to the forward edge of a sheet metal supporting plate 11 of channel cross-section (Fig. 3) which is also secured to back plate 1, this supporting plate occupying the space between side walls 3 and back plate 1 and plate 10. A 70 top plate 12 is secured over the upper edge of the back plate 1, and to the upper edges of side plates 3 which are extended above the posts 5 for this purpose. This top plate 12 is extended forwardly and downwardly 75 to provide a rounded portion 12^a, and is then inclined downwardly and rearwardly of casing 1 to provide a reflecting element 12^b. A sheet metal hood 13 is mounted within the upper portion of the casing and 80 has its upper wall disposed substantially parallel with top plate 12. The end walls 14 of this hood are spaced away from side walls 3 so as to leave spaces 15 which permit air flowing through slots 16 provided 85 through plate 11 to flow upwardly between side walls 3 and the end walls 14 of hood 13, this air circulating about the ends of the hood and through the space 16 between the hood and top plate 12, and then escaping 90 through the open work 12^c provided in element 12^a of top plate 12. In this manner the hood serves as a supplemental heating means, the hood itself being heated by the products of combustion which escape into the hood in a manner to be described. It is also to be noted that the cool air which enters the bottom of the casing through openings 17 provided in side walls 3 and back wall 1 for 100 this purpose, during its upward flow serves to effectively cool the side walls of the casing so as to prevent heating thereof, as well as the lower portion of the back wall.

A fireback 18 of clay or other suitable 110

refractory material is supported at its lower end in a sheet metal channel member 19 which is secured upon the upper face of plate 11. The upper end of back 18 is secured by sheet metal angle brackets 20 secured to the inner face of back plate 1. The body of this back is disposed in parallel spaced relation to plate 1 so as to leave an air space 21 between this plate and the back. The air which enters space 21 through slots 16 flows upwardly through this space and cooperates with back 18, which acts as a heat insulator, to effectively prevent heating of the back plate, a portion of this air flowing upwardly about the ends of hood 13, as previously noted, through the spaces 15 provided between the back and side walls and lateral extensions 22 of fireback 18, these extensions projecting forwardly of the body of back 18 and fitting snugly against end walls 3. In this manner the casing is maintained in a comparatively cool or unheated condition thus permitting the heater to be readily handled, or to be safely placed adjacent to a wall or other structure. The extensions 22 of fireback 18 co-operate with the body of the back to provide an elongated rectangular recess for reception of a plurality of tubular members or radiants 23 formed of clay or other suitable refractory material, the front wall of each of these radiants being of open or lattice work construction. The lower ends of the radiants rest upon the upper face of plate 11 and are held in alignment with rectangular openings 24 provided through the plate by front flange 19^a of channel member 19 and flanges 25 provided at the forward edges of openings 24. The radiants 23 have their upper end portions confined between the bight portion of a U-shaped holding member 26 formed of wire and the body of fireback 18, the arms 27 of member 26 being slidable through the top plate of hood 13. Downward movement of member 26 is positively limited by rectangularly disposed fingers 28 provided at the upper ends of arms 27, and this member is normally pressed toward the radiants by an upwardly and inwardly inclined flange 29 provided at the inner edge of a channel element 30 formed at the lower edge of a downwardly and rearwardly inclined locking and reflecting plate 31 extending from the lower edge of hood 13, this plate and the hood and element 12^b of top 12 being all secured together by means of screws passed through the same and nuts threaded onto these screws, or in any other suitable or preferred manner. The plate 31 extends the full width of the body or casing of the heater and is secured to the side walls 3 at each end by means of an angle member 32 the horizontal arm of which is secured to the central portion of

channel element 30, the vertical arm of member 32 being riveted or otherwise secured to the adjacent side wall 3. The arms 27 of member 26 fit snugly through the top of hood 13 and co-operate therewith to hold member 26 in vertical adjustment. This provides simple and efficient means whereby the radiants may be readily inserted or removed, as desired.

A gas burner 33 of any suitable or preferred type is supported within casing 1 below plate 11. The burner shown includes a sheet metal body or casing 34 which is provided in its upper wall with a plurality of rectangular series of perforations 35 disposed in alignment with the respective openings 24 through plate 11, and a mixing tube 36 for admitting a mixture of gas and air into casing 34. The mixture of gas and air flows through the openings 35 and is ignited in the usual manner, producing an intense heat which serves to quickly heat the radiants to incandescence. As any other suitable or preferred type of burner may be employed than that illustrated herein, and as the burner illustrated forms the subject matter of a separate application filed by me, it is not thought necessary to give a more detailed description or illustrate more fully the burner disclosed. The radiants 23 are enclosed by the fireback 18, the lateral extensions 22 serving to effectively prevent heating of side walls 3 and cooperating with the inwardly inclined elements 3^a for reflecting forwardly of the heater the heat generated in the radiants 23. The upwardly and inwardly inclined plates 9 and 10 and the downwardly and inwardly inclined element 12^b of top 12 and locking and reflecting plate 31 co-operate with elements 3^a of the side walls to reflect the heat generated outwardly and forwardly of the heater so as to obtain the maximum heating effect.

By the structure disclosed and above described I provide a heater the body or casing of which may be readily constructed from sheet metal and can, therefore, be readily produced at small cost while being of substantial construction and presenting a neat appearance. In addition, I provide simple and efficient means whereby the walls of the heater are effectively cooled so as to permit the heater to be safely handled at all times. This is accomplished by the cool air which enters the lower portion of the body or casing through the openings 17, a supplemental supply of cool air entering the casing through the open work 37 provided in plate 9 for this purpose.

As will be clear from Figure 3, the products of combustion escape from the upper ends of radiants 23 into the hood 13, these products escaping from the hood through an escape opening provided in back wall 1, a collar 38 being secured to the outer face of

the back wall about this opening and providing means adapted for reception of suitable piping for conducting the products of combustion to a flue or chimney. I thus obtain a maximum heating effect while avoiding the escape of the products of combustion into the apartment or room being heated.

Preferably, though not necessarily, I provide a wire guard 39 positioned in front of the radiants, this guard being provided at its upper end with a rod 40 the ends of which fit tightly into sleeves 41 secured through elements 3^a of side walls 3. These sleeves fit tightly about the ends of the rod and provide friction locks for holding the guard in raised position when it is desired to remove or replace any of the radiants. Normally, as will be understood, the guard is in lowered position.

It may be found desirable, by experience, to resort to changes in details of construction and arrangement of parts of the invention, and I intend to include all such variations, as fall within the scope of the appended claims, in this application in which a preferred form only of my invention is disclosed.

What I claim is:—

1. In a heater of the character described, a casing including side and back plates, lower upwardly and inwardly inclined front plates connecting said side plates, a supporting plate connecting the upper one of the front plates and the back plates, a refractory backing member mounted on said supporting plate and fitting between the side plates, said backing member being provided with lateral forwardly projecting extensions, radiants mounted on the supporting plate between said extensions, means for heating said members, a hood above the radiants, a downwardly and inwardly inclined reflecting and locking plate extending from the forward edge of the hood to the upper ends of the radiants and provided on its lower edge with a resilient element, and a member confined between said resilient element and the outer faces of the radiants for securing the latter in position.

2. In a heater of the character described,

a casing, a refractory backing member supported within the casing, a plurality of radiants mounted in front of and adjacent to said backing member, a hood positioned above the radiants, a downwardly and inwardly inclined reflecting and locking plate extending from the front of the hood to the upper ends of the radiants, said plate being provided at its lower edge with a channel element having an upwardly and rearwardly inclined inner flange, and a substantially U-shaped member having its arms slideable through the top of the hood, the bight portion of said member extending across the outer faces of the radiants adjacent to the upper ends thereof and said flange acting to resiliently press the U-shaped member toward the radiants.

3. In a heater of the character described, a casing, a refractory backing member supported within the casing, a plurality of radiants mounted within the casing adjacent to and in front of the backing member, a hood above said radiants, a plate extending from the forward edge of the hood to within a short distance of the outer faces of the radiants adjacent to the upper ends thereof, and a substantially U-shaped member having its arms slideable through the top of the hood and its bight portion extending across the outer faces of the radiants adjacent to their upper ends, said U-shaped member being confined between the lower edge of said plate and the radiants.

4. In a heater of the character described, a casing, a fireback supported in the casing, a plurality of radiants mounted adjacent to and in front of the fireback, a plate above and in front of the radiants and having its lower edge positioned adjacent to the upper ends of said radiants and a substantially U-shaped member mounted in front of the radiants for vertical adjustment, the lower edge of said plate contacting with said member and acting to press the same toward the radiants so as to confine the latter between said member and the fireback.

In testimony whereof I affix my signature.

ETIENNE WITZBERGER.
